UNITED STATES PATENT OFFICE

135,988

DESIGN FOR A VALVE CASING

Clarence M. Sears, Ayer, and Eddie E. Anderson,
Worcester, Mass.

Application December 16, 1942, Serial No. 109,046

Term of patent 7 years

To all whom it may concern:

Be it known that Clarence M. Sears and Eddie E. Anderson, both citizens of the United States, residing at Ayer, in the county of Middlesex and State of Massachusetts, and in the city of Worcester, county of Worcester, and State of Massachusetts, respectively, have invented a new, original, and ornamental Design for a Valve Casting, of which the following is a specification, reference being had to the accompanying drawing forming part thereof.

Fig. 1 is a top plan view of a valve casing, showing our new design;

Fig. 2 is a side elevational view thereof;

Fig. 3 is an elevational view of the other side thereof; and

Fig. 4 is an end elevational view thereof.

We claim:

The ornamental design for a valve casing, as shown,

CLARENCE M. SEARS.
EDDIE E. ANDERSON.
